Patented June 13, 1916.

UNITED STATES PATENT OFFICE.

LEONARD F. TIEFEL AND JOSEPH P. TIEFEL, OF BRAZIL, INDIANA.

SHINGLE.

1,186,619.

Specification of Letters Patent. Patented June 13, 1916.

Application filed July 23, 1914. Serial No. 352,680.

To all whom it may concern:

Be it known that we, LEONARD F. TIEFEL and JOSEPH P. TIEFEL, citizens of the United States, residing at Brazil, in the county of Clay, State of Indiana, have invented a new and useful Shingle, of which the following is a specification.

The present invention relates to improvements in shingles; one object of the invention, being the provision of a metallic shingle, each one of which is made from a single sheet of metal and so constructed and bent, as to provide overlapping and inter-engaging members so that when the same are assembled, a water tight roof is provided.

A further object of the present invention, is the provision of a metallic shingle, which is adapted to be placed upon the roof diagonally so that the single will coöperate with the two shingles below to produce an interlocking effect, one corner of the shingle being foreshortened and bent downwardly to provide a support or rest for the lowermost and normally unsupported portion of the shingle.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings Figure 1 is a plan view showing a portion of a roof with the singles in the proper position thereupon. Fig. 2 is a top plan view of one of the shingles. Fig. 3 is a bottom plan view thereof. Fig. 4 is a plan view upon a reduced scale of the blank for making the shingle. Fig. 5 is a section taken on line 5-5 of Fig. 1. Fig. 6 is a section taken on line 6-6 of Fig. 2. Fig. 7 is a section taken on line 7-7 of Fig. 1.

Referring to the drawings, the numeral 1 designates the roof sheathing, which is protected by the metallic shingles 2, 2', 2^a and 2^b, the shingles 2 being the conventional form of shingle while the shingles 2' constitute the eave shingle, the shingles 2^a constituting the shingles upon the edge of the roof, while the shingles 2^b constitute a corner thereof. The shingles 2', 2^a and 2^b are

partial shingles and each one is constructed as a part of one of the shingles 2. Each shingle 2, as shown in Fig. 4, is made from a single sheet of metal, the same being provided with the flanges 3 and the lip or rest 4 upon two of its edges and the corner of one of the two edges. The remaining two edges are provided with the flap members 5, which at their portions opposite to the foot rest 4 are provided with the V-shaped incisions 6, to provide the straight edge as clearly illustrated in Fig. 2 when the folded portion 7 is provided upon the dotted lines as illustrated in Fig. 4 which constitute a flange for receiving the flange 3 of the shingle disposed thereabove. The flange or flat portion 5 as illustrated in Fig. 2, is provided with the apertures *a* for the reception of the nails for securing the shingle to the roofing 1.

In assembling the present roofing, the shingles 2' and 2^b are attached to the roofing 1 with their ends adjacent the edge of the roofing, bent under so as to produce a neat effect, the shingle 2 disposed thereabove having its rest or projection 4 disposed to project below the lower edge of the roof 1, as clearly illustrated in Fig. 1. Where the shingles 2 are disposed directly above the regular shingles 2, the parts as at Fig. 7 will be in the position there shown in which portions of three of the shingles will be seen, one being the shingle adjacent to the roof, another to the left of the line 7-7, and the one directly above, the fold 7 of the lowermost shingle 2 being shown to receive the flange 3 of the shingle to the left while the fold 7 of the shingle to the left is disposed to receive the flange 3 of the uppermost shingle 2 whose foot rest 4 is disposed to engage and rest upon the lowermost shingle while it directly alines with the highermost. It will thus be seen that when the shingles are properly assembled that the rest or lug 4 will prevent pockets being formed at the apex or joining points of the shingles in the same line and that the end of the uppermost shingle will be protected due to the resting of the lower end thereof upon the shingle directly below. It will also be noted that in assembling the present shingles, that the flanges 3 in engaging the flanges 7 will guide the shingle into position so that the parts 5 will be properly presented to the portion 1

of the roofing so that nails or other fastening devices may be driven through the apertures *a* to secure the shingles in place.

Describing one of the shingles briefly, it consists of an approximately square body adapted to be placed diagonally upon a roof and provided at its lower edges with underlying reflexed flanges, said body having an obliquely arranged downwardly bent tongue at its lower corner between the lower ends of said flanges, and the body being provided at its upper edges with overlying reflexed doubled beads and nailing lips projecting from said beads, said lips being depressed adjacent the upper edges of the body to provide corrugations extending from the upper corner to the side corners of the body, the corrugations extending to the plane of the body, the lips sloping from the corrugations to said plane and having nail apertures between their edges and corrugations.

The corrugations of the nailing lips provide troughs for receiving any moisture which might pass by capillary attraction under the lower edges of the superposed shingles, and the moisture being collected in the corrugations will drain downwardly and pass from the side corners of one shingle onto the underlying shingles. This prevents the moisture from seeping back past the edges of the lips. Furthermore, it will be noted that the nail apertures are disposed between the free edges of the lips and said corrugations, whereby the moisture will not flow to said apertures. The corrugations thus serve to prevent moisture from passing to the apertures *a* and to the

edges of the lips, but serve to direct the moisture back to the next lower shingles. In view of the fact that the corrugations extend to the plane of the body and that the lips slope from the corrugations to the plane of the body with the nail apertures between said edges of the lips and the corrugations, when the nails are driven into place, the corrugations and free edges of the lips will be clamped upon the sheathing in an effective manner.

What is claimed is:

A metal shingle adapted to be placed diagonally upon a roof, comprising an approximately square body provided at its lower edges with underlying reflexed flanges, said body having an obliquely arranged downwardly-bent tongue at its lower corner between the lower ends of said flanges, and the body being provided at its upper edges with overlying reflexed doubled beads and nailing lips projecting from said beads, said lips being depressed adjacent the upper edges of the body to provide corrugations extending from the upper corner to the side corners of the body, the corrugations extending to the plane of the body, the lips sloping from the corrugations to said plane and having nail apertures between their edges and corrugations.

In testimony that we claim the foregoing as our own, we have hereto affixed our signatures in the presence of two witnesses.

LEONARD F. TIEFEL.
JOSEPH P. TIEFEL.
